ELIOT T. ANDERSON, OF ONTARIOVILLE, ILLINOIS, ASSIGNOR TO AMERICAN REENFORCED PAPER COMPANY, OF ATTLEBORO, MASSACHUSETTS, A CORPORATION OF MASSACHUSETTS

METHOD OF CURING CONCRETE

Application filed August 28, 1930. Serial No. 478,365.

This invention relates to a novel method of retarding the drying action of newly laid concrete so as to secure a slower and more gradual setting or hardening of the concrete structure.

It is well known in the art of concrete construction that newly laid concrete should dry slowly if the best results are to be secured, since too rapid drying, prevents proper hydration of the cement and tends to produce surface cracks and decreases the strength of the set concrete.

This retarding of the drying action of concrete is known as "concrete curing" and has been secured heretofore by frequently wetting the surface of the freshly laid concrete, or by covering the concrete with burlap and frequently wetting the same. When these prior methods of curing concrete are used water should be repeatedly applied to the concrete for a period of from one to several weeks, with the result that the repeated soaking of the concrete may involve considerable time and labor.

An important feature of the present invention therefore resides in an improved method of curing concrete whereby the need of repeatedly soaking the surface of the concrete is avoided. The present method is readily carried out by covering the surface of a freshly laid concrete floor, roadway or other area with a water-proof sheet or cover, adapted to retard the evaporation of the water of the concrete mixture from the setting concrete; and the invention relates more particularly to a covering of reenforced waterproof paper for the area of freshly laid concrete that is adapted to retard the evaporation of the moisture of the setting concrete and which is also sufficiently strong, durable and impervious to moisture to protect the surface of the concrete and keep it clean.

While the concrete curing feature of the waterproof covering of the present invention is of primary importance, the protection afforded the freshly laid concrete by the covering is also highly desirable, particularly in connection with the concrete floors of buildings, since these floors may be subjected

to heavy traffic and other injurious forces while the building is being constructed, and if the floors are not protected they are likely to become soiled and discolored by the falling concrete mixture or mortar and other building material during the construction of the building, and the floors may be permanently discolored or marred by the falling material and traffic unless protected.

One frequent source of injury to the concrete floors of buildings during the construction of buildings is due to the wet concrete falling from the newly constructed floor overhead onto the floor below and adhering thereto, but this difficulty is entirely overcome by the present invention since the falling concrete will adhere to the paper covering instead of the underlying floor and is readily removed with the paper.

Reenforced waterproof paper when employed in accordance with the present invention to cure and protect concrete may be subjected to extremely hard usage, since it may be covered with water or a wet muddy mixture of dirt and concrete for a period of days and the paper while in this condition may be subjected to the severe traffic of the workmen walking over its surface and hauling materials in wheelbarrows or carts. If the paper tears or disintegrates under this severe treatment or permits the dirty water to pass therethrough, the underlying concrete will be discolored or marred, and if the reenforcing fibers used to reinforce the paper contain coloring matter soluble in water the concrete may become stained or striped from the reenforcing fibers.

While either a reenforced or unreenforced, waterproof paper may be employed in practicing the method of the present invention, a strong, tough and durable paper which is water-proof to a pronounced degree is desirable to protect the underlying concrete when the covering sheet is subjected to the severe treatment above mentioned or is to remain in place upon the floor for some months, say throughout the completion of the entire building. These requirements, however, are satisfactorily met by the reenforced waterproof paper herein shown and

described, and which consists of two sheets of paper reenforced by unspun fibers laid relatively close together and firmly secured between the sheets of paper by a waterproof adhesive. After the erection of a building having the concrete floors covered with waterproof paper is practically completed, the protecting paper may be removed, whereupon the floors will be found to be well cured, clean and ready for use.

If the area of concrete to be cured is too large to be covered by a single width of paper of convenient dimension, then several or any desired number of widths of water-proof paper may be employed, but their adjacent edges should preferably be laid in overlapping relation so as to completely cover the underlying concrete, and these overlapping edges preferably are adhesively secured together so as to prevent the escape of moisture at the edges and also to hold the edges down and in place. While various adhesives may be employed for attaching the overlapping edges of the paper, a water-proof adhesive which will not be affected by the moisture of the damp concrete, or such water as may fall upon the paper, should be used.

It is important that the outer marginal edges of the covering sheet be firmly secured in place to prevent their accidental displacement, and also to prevent the wind from entering under the sheet and drying up the moisture needed for the proper hydration of the cement. This, however, is readily accomplished by adhesively securing the marginal edges of the covering sheet to the concrete surface.

The above and other features of the invention will be further understood from the following description when read in connection with the accompanying drawings illustrating one application of the present method.

In the drawings:—

Fig. 1 is a perspective sectional view of a portion of the covered floor of Fig. 2; and

Fig. 2 is a perspective sectional view of a room of a building or other structure having enclosing walls, and shows the concrete floor as covered with paper in accordance with the present method.

The method of the present invention is illustrated in the drawings in connection with a building construction having the concrete floor 10, side walls 11 and end wall 12, and the floor 10 is shown as provided with a moisture retaining covering formed of the sheets or strips of paper 13 disposed so that their adjacent edges overlap as shown.

One important object in providing the covering for the concrete area or floor 10 is to confine the moisture in the underlying concrete structure so as to retard its evaporation. The paper covering should therefore be applied to the concrete shortly after the con-

crete area is troweled or otherwise worked to present the desired smooth, upper surface, and while the inner structure of the concrete still retains a considerable amount of the water of the concrete mixture. The paper therefore should be placed upon the floor 10 about as soon as the concrete is sufficiently hard to permit the workmen to walk upon its surface without leaving foot prints. This may be the day the concrete is poured or the day following.

The paper in most cases should remain in place upon the concrete for from one to several weeks until the slow setting of the concrete is about completed, and as above stated may remain in place for months to protect the face of the floor 10 from dirt and foreign matter. The paper should therefore be firmly held in place so that it will not be displaced by the wind or the traffic over the floor. The overlapping marginal portions of the sheets of paper 13 are therefore preferably secured together, and it is desirable to employ an adhesive 14 for this purpose to form a tight joint between the sheets of paper to retain them in place and reduce the escape of moisture between their overlapping edges.

It is important that the sheets of paper be water-proof to prevent the moisture of the concrete from escaping through the texture of the paper and the water that falls upon the paper from penetrating therethrough to the underlying concrete, and also to reduce the tendency of the paper to disintegrate under the action of the moisture upon its upper and lower faces. It is also desirable to employ a water-proof adhesive at the joints 14 which will not be softened or otherwise affected by the moisture to which it may be exposed and release the paper, and while various water-proof adhesives may be used excellent results have been obtained through the employment of a water-proof adhesive formed from the viscous, milky substance secured from the rubber plant and which dries quickly when exposed to the atmosphere.

It is important that the outer marginal edges of the covering sheet of paper be retained in place adjacent the walls 11 and 12 so that the paper will not be picked up by the wind or otherwise displaced, and while these marginal portions may be held in place by the use of weights, such as wooden strips, excellent results are obtained by employing the water-proof adhesive above mentioned at the edges of the paper adjacent the walls 11 and 12 to secure the paper to the concrete 10, as indicated by 15.

As above stated, reenforced paper is preferably employed to cover the concrete 10 when the paper is to remain in place a relatively long time and is to be subjected to severe wear. The paper of Fig. 1 is therefore

shown as a multiply reenforced paper consisting of the sheets of paper 16 and 17 having reenforcing fibres 18 and secured therebetween in a straightened condition by a water-proof adhesive such as asphaltum. The reenforcing fibres are preferably unspun, such as sisal, and are distributed throughout the surface area of the paper to impart substantial resistance against tearing strains. Such fibres may extend longitudinally or transversely of the paper surface or they may extend in both directions, or in any direction best suited to impart the desired strength to the paper.

The use of unspun fibres such as sisal to reenforce the paper not only produces an extremely strong, tough and durable covering sheet, but possesses the further advantage, in that these unspun fibres will not stretch appreciably under tension, nor will they stain or discolor the underlying concrete as will low grade spun fibres.

In constructing buildings having concrete floors, it is the practice in some cases to form an underlying floor structure of concrete, then after the side walls of the building and rooms thereof are finished, a top layer of concrete forming the finished concrete floor is poured over the underlying rough floor structure. In other constructions the concrete floor is formed in a single operation by laying at one time sufficient concrete to form a floor of the desired final thickness, and when this method is used the various floors of the building may be completed before the side walls of the building are constructed, in which case the floor may be exposed to the weather for a period of many weeks.

The method of the present invention is well adapted for use in curing the concrete of either of the floor constructions just described, but when used in connection with the latter type of flooring, the paper covering will be exposed to the wind and rain and therefore should be firmly secured in place to prevent its displacement by the free sweep of the wind.

The multiply reenforced paper shown and described as formed of two sheets of paper adhesively secured together with a waterproof adhesive such as asphaltum and reinforced with unspun fibers is extremely tough, strong, and durable and is well adapted to protect and cure concrete floors and other concrete areas in accordance with the present invention.

A further advantage is secured through the use of the multiply, waterproof paper herein shown and described to cure concrete in accordance with the present invention, since this paper is clean to handle and since the waterproof adhesive such as asphaltum is confined between the two sheets of paper it does not come in direct contact with the

concrete to darken or stain the surface of the concrete.

While the method of curing concrete has been shown and described herein in connection with the floor of a building, it will be understood that the present method is also well adapted for use in curing concrete roadways, pavements and other concrete surfaces.

What is claimed is:

1. The method of curing concrete by retarding the evaporation of the moisture from the concrete structure, which consists in covering the surface of newly laid concrete that is exposed to the atmosphere with multiply waterproof paper formed of two sheets of paper secured together with a waterproof adhesive confined between the sheets so that this adhesive does not come in direct contact with the concrete, and retaining the waterproof paper in place upon the concrete during the concrete curing period.

2. The method in accordance with claim 1 wherein the paper sheets are strengthened by a reenforcement confined between the paper sheets by the waterproof adhesive.

3. The method in accordance with claim 1 wherein reenforcing filaments are secured by the waterproof adhesive between the paper sheets to strengthen and prevent rupture of the paper.

In testimony whereof, I have signed my name to this specification.

ELMER T. ANDERSON.
